UNITED STATES PATENT OFFICE.

JAMES Q. HORNE, OF LOCK HAVEN, PENNSYLVANIA, AND GORDON H. REIFSNIDER, OF LARCHMONT, AND WILLIAM A. ROWLEY, OF MAMARONECK, NEW YORK.

SANITARY LINING FOR GARBAGE CANS.

Application filed August 15, 1922. Serial No. 582,077.

To all whom it may concern:

Be it known that JAMES Q. HORNE, GORDON H. REIFSNIDER, WILLIAM A. ROWLEY, citizens of the United States of America, residing at, J. Q. HORNE, Lock Haven, Pa.; G. H. REIFSNIDER, Larchmont, N. Y.; W. A. ROWLEY, Mamaroneck, N. Y., in the county of Clinton (Pa.), Westchester (N. Y.), and State of (Pennsylvania), (New York), have invented certain new and useful Improvements in Sanitary Linings for Garbage Cans, of which the following is a specification.

This invention relates to certain new and useful improvements in hygienic and sanitary linings for garbage cans or pails.

Garbage cans, as at present used, consist of a container of some sort, preferably metal with handles on its sides, or a bail by which it can be moved from place to place, and a top usually of the same material as the body, which fits down tightly over the upper edge of the container and prevents the escape of the stench of the malodorous refuse. With this refuse which for the most part, as a rule, is of rather dry consistency, there is frequently mixed considerable matter which is only partially dry such as the viscera of animals, the rinds of fruit and sometimes dirty liquid, and these naturally sink to the bottom of the can which sooner or later rusts into holes.

Further, the garbage resting against the bottom and sides of the can makes the container exceedingly foul. In order to avoid this, at least to some extent, it has become a habit with a good many persons to take a piece of wrapping paper or a discarded newspaper and put it into the bottom of the container and around the lower adjacent sides into which they dump the garbage, and this keeps the can somewhat more cleanly than when such method is not pursued; newspapers, however, are made of rather a poor quality of paper which soon absorbs the filthy liquid and resting against the bottom part of the container, soon rusts it out.

One of the objects of our invention, therefore, is to provide a lining for garbage pails made of strong paper, either plain or chemically treated, such as with creosote or oil, or both. The lining may also be made of waxed paper or of what is known as "glassine" paper, and cardboard may be

used after it has been treated so as to render it more impervious and more resistive to liquid penetration.

Another object of our invention is to provide a lining of the character described made up in different regular or stock sizes so as to accommodate the different sizes of garbage receptacles sold on the market, each lining being purchased to fit the container used and to be easily slipped into place when a new lining is required.

Another object of our invention is to provide a lining such as above described with two or more tabs at its upper edge by which the lining with its contents of garbage may be easily lifted out and disposed of.

A further object of our invention is to so crease that part of the lining which comes into contact with the bottom and sides of the can as to make it easily adjustable when it is inserted therein.

A still further object of our invention is to make this lining for the can of a single piece of material of such shape and so shaped that it may be folded up into a flat rectangular parcel of so small a size that a number may be bound up into a single bundle or package and sold, as for instance, by the dozen.

With these and other objects in view which may be incident to our improvements, the invention consists in the parts and combinations to be hereinafter set forth and claimed, with the understanding that the several necessary elements comprising our invention may be varied in construction, proportions and arrangement, without departing from the spirit and scope of the appended claims.

In order to make our invention more clearly understood, we have shown in the accompanying drawings means for carrying the same into practical effect without limiting the improvements in their useful applications to the particular constructions, which for the purpose of explanation, have been made the subject of illustration.

In the drawings:

Figure 1 is a perspective view of a garbage can with its top removed and one side partly broken away so as to show the lining in place;

Figure 2 is a plan view of our lining as it appears when unfolded and stretched out;

Figure 3 is a plan view of our lining

ready to be packed into a bundle for market;

Figure 4 is a view looking from above down into the garbage, showing the lining as it would appear ready for use, the can not being shown;

Figure 5 is a view showing one-half of an unfolded lining with a tab on each octagonal edge instead of on each alternate octagonal edge as shown in Fig. 2;

Figure 6 is a detail view showing the lining as it appears when the first folds are opened, and

Figure 7 is a detail view showing a dozen of the linings packed in one bundle or package ready for sale by the retail trade.

The numeral 1 represents a garbage can of the usual or any approved construction, the one shown being made of galvanized iron and of a cylindrical formation circular in cross-section. It comprises a bottom 2 and sides 3, the latter being corrugated so as to make the structure more rigid and less likely to be indented by the rather rough handling which receptacles of this kind are likely to receive.

The numeral 4 represents a sheet of paper or cardboard, waxed, oiled or otherwise chemically treated or prepared, with the express object in view of making it strongly resistant to liquid penetration. The sheet is then cut in the shape of an octagon and properly creased by any suitable means, as shown in Fig. 2. As will be seen from an inspection of the design shown in this figure, each octagonal edge forms the base of a rectangle 5, and right angle triangles 6 and 7, one on each side thereof, whose apices 8 and 9 respectively point toward the center 10 of the octagon. The top 11 of each rectangle forms the base of a triangle whose apex is the center of an interior octagon 12 and of the exterior octagon circumscribed thereabout. It is to be observed that the lining is cut a trifle smaller in height and width than the can in which it is intended to be placed.

The manner of creasing the octagonal sheet of paper so as to enable it to be reduced to a small parcel as desired by the trade is to crease the sheet first along the line 15-15; second, to crease said sheet along the line 16-16; thirdly, to crease the said sheet along the line 17-17. The original sheet of paper is then folded along the several creases and is reduced to the size of a triangular wad of paper described by the lines 15-10-17. The tip 18-10-19 of this triangle is then turned over toward the base of the triangle, (see Fig. 6) and the sides 15-18-20, and 21-19-17 folded towards the triangular sides of said tip, and the parcel presents the appearance seen in Fig. 3.

It will be noticed that each alternate outer

edge of the original octagon sheet is provided with a tab 25 by which the lining may be grasped and the edges drawn inwardly toward the center when it is desired to lift the lining with the refuse therein from the can and to install a new lining. These tabs have been found very helpful in drawing together the sides of the bundle just prior to removal. They may be made integral with the sheet, or pasted on afterwards and their number may be decreased or diminished, as desired by the trade. Further, they may be turned in upon the sheet when the several folds are made, as shown in dotted lines in Fig. 3, or stick outward from the parcel as seen in Fig. 6.

The manner for using the lining is as follows: Open the parcel and spread it out to its full extent over the container to be lined and press the interior octagonal portion thereof towards the bottom of the can with a gentle movement outwardly from the center in an endeavor to smooth out the creases where the sheet has been folded. Upon placing the garbage within the lining, the latter will tend to spread the lining against the walls of the can.

While we have shown and described the preferred embodiment of our invention, we wish it to be understood that we do not confine ourselves to the precise details of construction herein set forth, by way of illustration, as it is apparent that many changes and variations may be made therein, by those skilled in the art, without departing from the spirit of the invention, or exceeding the scope of the appended claims.

We claim—

1. As an article of manufacture, a removable sanitary lining for garbage cans comprising a sheet of paper of the shape of a regular polygon so folded and refolded upon itself as to produce a flat rectangle, which when unfolded by reason of the creases made by the folds, is easily positioned in a cylindrical can of the size for which said lining is made.

2. As an article of manufacture, a removable sanitary lining for garbage cans comprising a polygonal sheet of paper so folded and refolded upon itself as to form a flat triangle, the sides of which are then folded toward and partially upon one another, and the apex of which is folded within the V-shaped space between the sides so as to make the sheet thus folded a flat rectangle, and which sheet of paper when unfolded, by reason of the creases made by the folds is easily positioned in a cylindrical can of the size for which said lining is made.

3. As an article of manufacture, a removable sanitary lining for garbage cans comprising a polygonal sheet of paper so folded and refolded upon itself as to form a flat triangle, which triangle is folded upon itself

- so as to form a triangle of a reduced size, the sides of which are then folded toward and partially upon one another, and the apex of which is folded within the V-shaped space between the sides so as to make the sheet thus folded a flat rectangle, and which sheet of paper when unfolded, by reason of the creases made by the folds is easily positioned in a cylindrical can of the size for which said lining is made.
- 5 the size for which such lining is made.
4. As an article of manufacture, a removable sanitary lining for garbage cans comprising an octagonal sheet of paper so folded and refolded upon itself as to form 5 a flat triangle, the sides of which are then folded toward and partially upon one another, and the apex of which is folded within the V-shaped space between the sides so as to make the sheet thus folded a flat rectangle, and which sheet of paper when 20 unfolded, by reason of the creases made by the folds is easily positioned in a cylindrical can of the size for which said lining is made.
- 10 In testimony whereof we affix our signatures.
